SAMUEL REYNOLDS, OF ALLEGHENY CITY, PENNSYLVANIA.

Design No. 4,354, dated September 13, 1870.

DESIGN FOR A TRACE-CARRIER FOR HARNESS.

The Schedule referred to in these Letters Patent and making part of the same

To all whom it may concern:

Be it known that I, SAMUEL REYNOLDS, of the city and county of Allegheny and State of Pennsylvania, have invented and produced a new and original Design for Trace-Carrier for Harness, of which the following is a specification.

The nature of my design is fully represented in the accompanying drawing, to which reference is made.

Figure 1 is a top view or plan of the trace-carrier.

Figure 2 is a side elevation of the same.

In the accompanying drawing—

B represents the ring to which the harness is attached.

A A represent the hooks used for carrying the traces of the harness.

I represents the guard for preventing the driving-rein from becoming entangled in the hooks.

The advantage of my design and form of trace-carrier, herein described and shown, consists in the facility it affords in molding it, and its adaptation to the form of that part of the harness which is to be attached to the ring B, and also in the facility afforded for finishing and cleaning, or polishing or plating the trace-carrier.

Having thus described the nature of my design,

What I claim as my invention is—

The design for a trace-carrier, as described and shown in the accompanying drawing.

SAMUEL REYNOLDS.
